UNITED STATES PATENT OFFICE

161,206

POT COVER HOLDER

Paula Redlich, New York, and Erwin C. Steiner,
Jackson Heights, N. Y.

Application January 23, 1950, Serial No. 7,407

Term of patent 14 years

(Cl. D44—29)

To all whom it may concern:

Be it known that we, Paula Redlich, a citizen of the United States of America, residing at New York, New York, and Erwin C. Steiner, a citizen of the United States of America, residing at Jackson Heights, L. I., New York, have invented a new, original, and ornamental Design for Pot Cover Holder of which the following is a specification, reference being had to the accompanying drawing, forming a part hereof.

Fig. 1 is a top plan view of a pot cover holder, showing our new design;

Fig. 2 is a side elevational view; and
Fig. 3 is a bottom plan view.

We claim:

The ornamental design for a pot cover holder, as shown.

PAULA REDLICH.
ERWIN C. STEINER.
